UNITED STATES PATENT OFFICE

94,465

DESIGN FOR A SANDAL OR SIMILAR ARTICLE

Albert M. Bressler, New York, N. Y.

Application October 13, 1934, Serial No. 53,612

Term of patent 7 years

To all whom it may concern:

Be it known that I, Albert M. Bressler, a citizen of the United States, and a resident of New York city, county of New York, and State of New York, have invented a new, original, and ornamental Design for a Sandal or Similar Article, of which the following is a specification, reference being had to the accompanying drawing, forming part thereof.

In the drawing:

Fig. 1 is a side perspective view of the sandal embodying the present design;

Fig. 2 is a side view of the opposite side of the sandal;

Fig. 3 is a rear view in elevation with part of

the broken out lines of the straps omitted for convenience in illustration.

The dominant feature of the present design is the ornamental effect produced by the heel having the contour substantially as shown, and more particularly in that the heel is of medium height and slopes outwardly from the top to the bottom thereof on all sides and the heel, being preferably made of wood, is further ornamented by the natural grain of the wood.

I claim:

The ornamental design for a sandal or similar article substantially as shown and described.

ALBERT M. BRESSLER.
